(57) **CLAIM**

The ornamental design for a grill, as shown and described.

DESCRIPTION

FIG. 1 is a perspective view of a grill showing my new design.

FIG. 2 is a right side view of the grill shown in FIG. 1, the left side view being a mirror image thereof;

FIG. 3 is a top view of the grill shown in FIG. 1;

FIG. 4 is a bottom view of the grill shown in FIG. 1;

FIG. 5 is a front view of the grill shown in FIG. 1; and,
FIG. 6 is a rear view of the grill shown in FIG. 1.

The broken lines in the views shows environmental features
which are for illustrative purposes only and form no part of
the claimed design.
